UNITED STATES PATENT OFFICE

2,050,472

TOILET SEAT AND COVER

Francis A. Steadman, Marietta, Ohio

Application June 27, 1934, Serial No. 732,711

1 Claim. (Cl. 4—234)

This invention relates to improvements in toilet seats and seat covers, and has among its more important objects to provide a one-piece cast metal toilet seat which may be produced at relatively low cost and which is strong, durable and sanitary; to provide a cooperating one-piece cast metal seat cover which likewise may be produced at relatively low cost and which is strong, durable and sanitary; to provide novel hinge means for mounting the seat and the cover on a bowl, and to provide novel means for mounting rubber or equivalent bowl engaging stops on the seat and rubber or equivalent seat engaging stops on the cover.

With the foregoing and various other objects in view which will become more fully apparent as the nature of the invention is better understood, the same consists in the novel features of construction, combination and arrangement of parts as will be hereinafter more fully described, illustrated in the accompanying drawing and defined in the appended claim.

In the drawing, wherein like characters of reference denote corresponding parts in the different views:—

Figure 1 is a top plan view of a toilet seat and cover embodying the features of the invention.

Figure 2 is a section on the line 2—2 of Figure 1.

Figure 3 is a section on the line 3—3 of Figure 1.

Figure 4 is a detail sectional view illustrating a seat of modified form; and

Figure 5 is a detail view of a modified form of lug and bumper.

A primary feature of the invention is to provide a seat that is waterproof and therefore will not be affected by moisture or water even if it is subjected to inundation by flood.

Referring to the drawing in detail, S designates, generally, the present toilet seat and C the cover therefor. Both the seat and cover are of one-piece construction and may be pressed or stamped, but are preferably cast, from aluminum or aluminum alloy or other suitable light weight metal or alloy, whereby they are strong, durable, easy to handle and devoid of insanitary joints such as are present in plural part seats and covers, particularly the built up or veneered types of wooden seats and covers.

The seat S has cast integral therewith, at its rear, a pair of rearwardly extending, laterally spaced hinge lugs 10, 10 which are apertured for the reception of hinge pins 11, 11 projecting laterally from the upper end portions of bolts 12, 12 which are secured to the rear of the bowl B, whereby the seat and cover are mounted on the

bowl for swinging movement between raised and lowered positions.

The cover C also has cast integrally therewith, at its rear, a pair of laterally spaced hinge lugs 13, 13 which are apertured for the reception of the hinge pins 11, 11 and which are curved downwardly as shown for alinement with the lugs 10, 10, said lugs 13, 13 fitting between the lugs 10, 10 as shown to brace the cover against sidewise movement relative to the seat, the hinge pins 11, 11 passing, respectively, through related lugs 10, 13 so that the single pair of hinge pins serve to mount both the seat S and the cover C on the bowl B for swinging movement between raised and lowered positions.

By reference to Figs. 2 and 3 of the drawing it will be observed that both the seat S and the cover C are of open-bottom, hollow construction, whereby they are of light weight and may be cast readily and economically. Moreover, it will be observed by reference to Figs. 1 and 2 that lugs 14 are cast integrally with both the seat and the cover and depend from the top walls thereof into the hollow open bottom spaces of said seat and cover whereby they are entirely concealed when the seat and cover are lowered, said lugs serving for the attachment to the seat and cover of rubber or equivalent bumpers 15, 16, respectively, for engagement with the upper edge of the bowl and the top of the seat, respectively, to cushion the seat and cover when they are dropped to their lowered positions. In this connection it will be noted that the seat is provided with three lugs 14, one of which is disposed at the front of the seat and the other two at the sides thereof, respectively, whereby the seat, when lowered, is firmly supported at three points against wobbling. Also, it will be noted that the cover is provided with only a single lug 14 and bumper 16 located at the front thereof, and that upon the top or outer face of the cover is secured a single bumper 17 to cushion the cover when it is raised, the fastening screw 18 for the bumper 17 preferably extending into the lug 14 of the cover to obtain greater strength for the mounting of the bumper 17.

If desired, the seat S may be provided at its front with a shield or guard 19 as illustrated in Fig. 4 of the drawing, said shield or guard being formed as an integral downward extension of the rear wall of the front portion of the seat.

Figure 5 illustrates a modified form of bumper lug and bumper, wherein the lug 14a is knurled or burred on the outer surface to receive a slip-on type of rubber bumper 15a. The type of bumper

illustrated in this figure has the advantage that it will wear completely down to the lower face of the lug before it needs replacement.

With further reference to the bumper lugs it may be pointed out that the same may be fastened to the seat or seat cover by welding or by other fastenings in the event that the seat or cover is pressed or stamped. In that connection, it may be pointed out that one of the features of the invention is to provide a bumper lug which is completely housed and concealed within the transversely arched portion of the seat or seat cover, so that only a portion of the cushioned bumper projects beyond the plane of the particular member which carries the same. This not only has the advantage of concealing the metallic lug from view, but tends to avoid contact of the metallic seat with the porcelain and makes it possible to provide a deeper cushion than if the lugs were extended or projected beyond the plane of the seat itself.

Also, if desired, bushings of bronze, brass or other suitable material may be provided to fit the apertures in the hinge lugs 10, 10 and 13, 13 and to receive the hinge pins 11, 11 to reduce wear and provide for longevity of the hinge mounting of the seat and cover.

The seat and lid may be finished by buffing and polishing or by painting. In any case, the seat and cover are devoid of joints or the like, will not absorb moisture, and therefore may readily be cleaned and maintained clean and sanitary. Moreover, as aforesaid, both the seat and cover obviously are capable of being cast easily and at low cost and when installed upon a bowl obviously are not liable to become broken or damaged, but possess substantially indefinite life.

From the foregoing description considered in connection with the accompanying drawing it is believed that the construction and the numerous advantages of the invention will be readily understood and appreciated. It is desired to point out, however, that while only a single specific embodiment of the invention has been illustrated and described, the same is readily capable of modification within the spirit and scope thereof as defined in the appended claim. 10

I claim:—

In a device of the class described, a seat/member comprising a body of transversely arched hollow formation, integral rearwardly extending perforated hinge lugs disposed in the plane of the 15 body and located at each side of the longitudinal center thereof, a bumper lug cast integral with the under arched face of the seat body at the front thereof and disposed at the longitudinal center of the seat, a cover of open bottom hollow 20 formation, a pair of rearwardly extending integral perforated hinge lugs on the cover and disposed at either side of the longitudinal center thereof, said cover hinge lugs being downwardly curved and spaced closer together than the seat hinge 25 lugs, thereby to be disposed at the inside faces of said seat hinge lugs to brace the cover against sidewise movement relative to the seat and also to bring the perforations of both sets of hinge lugs into registry, an integral bumper lug formed 30 on the under side of the cover at the center thereof substantially to align vertically with the bumper lug on the seat, and bolt members having laterally projecting hinge pins extending inwardly through the perforations of both sets of hinge lugs to pivotally connect the same together. 35
